[57] CLAIM

The ornamental design for a children's shopping cart, as shown and described.

DESCRIPTION

FIG. 1 is a right side elevational view of a children's shopping cart showing my new design;

FIG. 2 is a left side elevational view;

FIG. 3 is a front elevational view;

FIG. 4 is a rear elevational view;

FIG. 5 is a top plan view;

FIG. 6 is a bottom plan view; and,

FIG. 7 is a perspective view.

The broken lines of FIGS. 1 through 6 are for illustrative purposes only and form no part of the claimed design.
